The leading features of my design consist in a suspender-buckle piece having an outer member representing a strap and having curved margins and formed at or near its central portion with a transverse bulge or curvature, an inner member likewise representing a strap and having a wide upper portion center, the narrow portion of the inner member crossing in comparatively straight lines 25 the bulge or curvature in the outer member, and circular ornamentations appearing on the face of the inner member.

A designates the inner member, and B the outer member. These two members are 30 brought together at their end portions, and the outer member at its center is bulged outwardly or from the inner member.

C designates a button ornament which is located at one point of engagement of the 35 two members, and D designates an ornament which appears as a depression and is located near the other point of engagement of the two members.
